EXPANSIBLE CUTTER TOOL

John W. MacClatchie, Los Angeles, Glenn D. Johnson, Compton, and Carl A. Thies, Huntington Park, Calif., assignors to MacClatchie Manufacturing Company of California, Compton, Calif., a corporation of California

Application November 30, 1936, Serial No. 113,298

14 Claims. (Cl. 255—76)

This invention relates to expandable cutter tools and is particularly applicable to well drilling tools for enlarging the bore of a well, the invention being illustrated and described in connection with that type of tool wherein an expandable cutter scrapes the wall of the well bore.

It is an object of the invention to expand a cutter by relative longitudinal movement of a mandrel, with a simple but efficient operating connection between the mandrel and the cutter.

It is a further object of the invention to circulate a washing medium through the bore of a hollow mandrel, with a port in the mandrel discharging a part of the washing medium at the cutter, and with said port forming a part of the operating connection for expanding the cutter.

It is a still further object of the invention to utilize pressure of the washing medium in the bore of the mandrel for expanding the cutter, by restricting the bore of the mandrel by means of the contracted cutter so that the pressure of the washing medium is directed against the cutter for expanding the same.

It is a still further object of the invention to actuate the mandrel by pressure of the washing medium, and to provide simple means for initially restricting flow of the washing medium through the bore of the mandrel so that the pressure of the flow is utilized for shifting the mandrel, with this restriction subsequently removed so as to permit free circulation of the washing medium.

It is a still further object of the invention to arrest operative movement of the mandrel before the cutter reaches its fully expanded position, with a lost motion operating connection permitting the cutter to then fully expand, and with said lost motion connection eliminating wear at the operating connection when the cutter is expanded.

Further objects of the invention will be readily understood from the following description of the accompanying drawing, in which:

Fig. 1 is a side elevation of the tool, partly in axial section and showing its cutters contracted.

Fig. 2 is a similar view showing the cutters expanded.

Figs. 3 and 4 are transverse sections on the lines 3—3 and 4—4 of Figs. 1 and 2 respectively.

The invention is illustrated in connection with an expandable cutter tool for scraping the wall of a well bore, and in the illustrated embodiment of the invention the tool has three cutters equidistantly circumferentially spaced. The cutters are mounted on a body 1 which is adapted for incor-

poration in a usual drill string, preferably by means of a sub 2 which is threaded to the upper end of the body 1 and which has a threaded connection 3 at its upper end, with the lower end of the body 1 also having a usual threaded connection (not shown). The cutters are mounted in radial slots 4 which are formed in the body and which communicate with an axial bore 5 of the body. A mandrel 6 is slidable in the bore 5 and an operating connection is provided between the mandrel and the cutters for expanding the latter.

The cutters are shown adapted for swinging movement to their expanded position, and for this purpose cutters 7 may be pivoted on pins 8 which extend across the slots 4 and which may be removably held in place as shown at 9. The cutters when contracted are contained within the slots 4 as shown at Fig. 1, and when expanded swing outwardly and upwardly to the position shown at Fig. 2, with their cutting edges 7a adapted to scrape the wall of a well bore when the tool is rotated.

The mandrel 6 is hollow, and the operating connection between the mandrel and the cutters preferably includes a tubular extension 6a of the mandrel which is ported as shown at 10 for reception of lugs 11 which are preferably integral with the cutters 7. The tubular extension 6a preferably has flattened surfaces 12 aligning with the respective cutters, with the ports 10 formed in said flattened surfaces; and the lower end of the extension 6a may be of restricted diameter below the ports 10 adapting said lower end of the extension for sliding reception in the lower end of the bore 5 which is preferably of restricted diameter as shown at 5a.

When the mandrel is elevated as shown at Fig. 1 the lugs 11 are received in the ports 10 with the cutters 7 swung to contracted position abutting the mandrel extension 6a. In this position the lugs 11 project into the bore of the tubular extension 6a so as to appreciably restrict said bore as shown at Fig. 3, and the lugs have surfaces 11a which when the cutters are contracted taper downwardly as shown at Fig. 1, whereby downward pressure in the bore of the hollow mandrel is directed against the surfaces 11a so as to tend to swing the cutters 7 toward their operative position. The lugs 11 also have surfaces 11b which when the cutters are contracted engage the upper ends of the ports 10, so that downward movement of the mandrel shifts the lugs 11 for swinging the cutters toward their operative position.

The mandrel 6 may be shifted to expand the 55

cutters by fluid pressure in the bore of the tool, and for this purpose the sub 2 may have a bore 15a which forms a cylinder 15 for a piston, with the bore of the sub open at its upper end for communication with the bore of the drill string in which the tool is incorporated. The piston is fixed to the upper end of the hollow mandrel for pressure responsive downward movement in the cylinder 15 so as to downwardly shift the mandrel, and in the illustrated embodiment of the invention the piston is shown as including an abutment 16 integral with the hollow mandrel 6, with a piston rubber 17 which preferably has a reinforcement plate 18, secured to the abutment 16 by means of a follower 19.

When the cutters 7 are contracted and the hollow mandrel 6 is elevated as shown at Fig. 1, a plug 20 which is supported by the sub 2 preferably extends into the upper end of the bore of the hollow mandrel so as to appreciably restrict flow through said bore and thus maintain appreciably pressure against the piston 17 for depressing the mandrel and thereby swinging the cutters toward their operative position; and the restricted flow past the plug 20 and through the bore of the hollow mandrel exerts pressure against the surfaces 11a of the lugs 11 for aiding in swinging the cutters toward their operative position.

Downward movement of the mandrel 6 is preferably terminated by the abutment 16 engaging a cooperating abutment surface 22 at the upper end of the body 1, and with the parts in this position the mandrel has preferably not yet swung the cutters to fully expanded position. However the cutters are so nearly fully expanded as to engage the wall of the well bore so that the weight of the drill string completes the swinging movement of the cutters to their fully expanded position as determined by abutment of their surfaces 11b against the upper ends of the slots 4. This final swinging movement of the cutters after downward movement of the mandrel has been arrested, spaces the lugs 11 from the upper ends of the ports 10 as shown at Fig. 2, and as a result of this lost motion connection the tool may be operated with its cutters expanded, with no wear between the lugs 11 and the ends of the ports 10.

By the time downward movement of the mandrel 6 has been arrested its bore will have shifted clear of the plug 20 as shown at Fig. 2, so that the entire flow through the drill string is then directed through the bore of the mandrel, and when the cutters have been fully expanded their lugs 11 will have been swung clear of the bore of the mandrel so as to offer no obstruction to this flow. Flow is thus directed through the hollow mandrel extension 6a and thence downwardly through the lower portion of the bore 5 and through the bore of that portion of the drill string which depends from the body 1, so as to maintain usual circulation through the drill string. At the same time the lugs 11 of the expanded cutters are swung clear of the lower portions of the slots 10 which are of such appreciable length that these unobstructed lower portions of the slots form outlets of appreciable area through which an appreciable portion of the flow in the bore of the hollow mandrel is directed laterally outwardly through the slots 4 and just below the expanded cutters.

When the cutters are to be contracted the drill string is elevated, and as a result of binding engagement of the expanded cutters with the wall of the well bore the cutters are swung toward their contracted position. Further contraction of

the cutters results if the drill string is withdrawn through an upper portion of the well bore, such as a casing string, which is of smaller diameter than that defined by the expanded cutters, and complete contraction of the cutters is preferably assured by mounting a spring 30 in the bore 5 around the mandrel 6, between the abutment 16 and a supporting collar 31 which seats on a shoulder in said bore. As soon as the force tending to hold the cutters in expanded position is relieved by elevating the drill string, the spring 30 thus tends to retract the mandrel 6 so that the lower ends of its ports 10 engage the lugs 11 for contracting the cutters.

The invention thus provides an arrangement whereby the ports 10 cooperate with the lugs 11 for expanding and contracting the cutters, with said ports also serving as outlets for discharge of a washing medium through the slots 4 and below the expanded cutters, and with said ports also permitting projection of the lugs 11 into the bore of the hollow mandrel when the cutters are contracted, so that flow through the hollow mandrel and directed against the lugs may aid in expanding the cutters.

In the claims, we have used the word "body" to include the body 1 and the sub 2, and similar structures.

We claim:

1. In an expandable cutter tool, a body having a radial slot, a hollow mandrel mounted in said body, said mandrel having a lateral port communicating with said radial slot, a cutter mounted in said radial slot having a projection cooperating with the port for shifting the cutter by movement of the mandrel, and means for directing a washing medium through the hollow mandrel for discharge at the port.

2. In an expandable cutter tool, a body having a radial slot, a hollow mandrel mounted in said body, said mandrel having a lateral port communicating with said radial slot, a cutter mounted in said radial slot having a projection cooperating with the port for shifting the cutter by movement of the mandrel, and means for directing a washing medium against the mandrel for moving the same, with said washing medium directed thence through the hollow mandrel for discharge at the port and through said radial slot below said cutter.

3. In an expandable cutter tool, a hollow mandrel, a cutter having a projection extending into the bore of the hollow mandrel, and means for directing pressure in the bore of the hollow mandrel and against the projection for shifting the cutter.

4. In an expandable cutter tool, a hollow mandrel, a cutter having a projection extending into the bore of the hollow mandrel, means for shifting the cutter by movement of the mandrel, and means for exerting pressure in the bore of the hollow mandrel and against the projection for aiding in shifting the cutter.

5. In an expandable cutter tool, a hollow mandrel, a cutter having a projection extending into the bore of the hollow mandrel, means for shifting the cutter by movement of the mandrel, and means for directing pressure against the mandrel for moving the same, with said pressure directed thence through the hollow mandrel and against the projection for aiding in shifting the cutter.

6. In an expandable cutter tool, a hollow mandrel having a lateral port, a cutter having a projection extending through the port and into the bore of the mandrel for shifting the cutter by

- movement of the mandrel, and means whereby a washing medium may be directed against the mandrel for moving the same, with said washing medium directed thence through the hollow mandrel and against the projection for aiding in shifting the cutter and for discharge through the port. 5
7. In an expansible cutter tool, a body, a hollow mandrel movable in the body, a plug fixed to the body and extending into the bore of the hollow mandrel when the mandrel is retracted and being clear of the bore of the mandrel when the mandrel is projected, a cutter carried by the body, and means for moving the cutter by projection of the mandrel. 10
8. In an expansible cutter tool, a hollow mandrel having a lateral port, means for restricting the bore of the hollow mandrel when the mandrel is retracted and for opening the bore of the hollow mandrel when the mandrel is projected, and a cutter having a projection cooperating with the port for shifting the cutter by projection of the mandrel. 15
9. In an expansible cutter tool, a mandrel, means for limiting movement of the mandrel, a cutter, and a lost motion connection for shifting the cutter by movement of the mandrel and permitting continued shifting of the cutter after movement of the mandrel has been stopped. 20
10. In an expansible cutter tool, a hollow mandrel having a lateral port, means for limiting movement of the mandrel, and a cutter having a projection adapted for engagement by the wall of the port for shifting the cutter by movement of the mandrel and permitting continued shifting of the cutter after movement of the mandrel has been stopped so as to space the projection from said wall of the port. 25
11. In an expansible cutter tool, a hollow body having a slot, a cutter in said slot, a hollow mandrel movable in the bore of the body and hav- 30
- ing a lateral port, and a projection on the cutter adapted for engagement by the wall of the port for expanding the cutter by movement of the mandrel. 35
12. In an expansible cutter tool, a hollow body having a slot, a cutter in said slot, a hollow mandrel movable in the bore of the body and having a lateral port, and a projection on the cutter adapted for engagement by the wall of the port for expanding the cutter by movement of the mandrel, the projection extending into the bore of the hollow mandrel when the cutter is contracted so that pressure directed through the bore of the hollow mandrel is exerted against the projection for aiding in expanding the cutter. 40
13. In an expansible cutter tool, a hollow body having a slot, a cutter in said slot, a hollow mandrel movable in the bore of the body and having a lateral port, a projection on the cutter adapted for engagement by the wall of the port for expanding the cutter by movement of the mandrel, and means for limiting said movement of the mandrel, the port engaging the projection so as to permit continued expansion of the cutter after movement of the mandrel has been stopped, so as to space the projection from the said wall of the port. 45
14. In an expansible cutter tool, a hollow body having a slot, a cutter in said slot, a hollow mandrel movable in the bore of the body and having a lateral port, a projection on the cutter adapted for engagement by the wall of the port for expanding the cutter by movement of the mandrel, and a plug fixed to the body so that it is received in the bore of the hollow mandrel when the mandrel is retracted but clears the bore of the hollow mandrel when the mandrel is projected. 50
